UNITED STATES PATENT OFFICE.

GEORG RIETKÖTTER, OF HAGEN, GERMANY.

ELECTROMAGNETIC ORE-SEPARATOR.

1,074,068.

Specification of Letters Patent. Patented Sept. 23, 1913.

Application filed October 30, 1912, Serial No. 728,644. Renewed June 26, 1913. Serial No. 775,968.

To all whom it may concern:

Be it known that I, GEORG RIETKÖTTER, a subject of the Emperor of Germany, and resident at Hagen, Germany, have invented 5 certain new and useful Improvements in Electromagnetic Ore-Separators.

Electro-magnetic ore-separators having a stationary system of magnets and a revolving drum-shaped casing are well-known. 10 Furthermore, in machines of this class heretofore known, the system of magnets is arranged on a stationary shaft and the cylindrical casing is provided with independent side-disks, to one of which rotation is imparted by means of a belt or the like. This 15 rotation is transmitted to the opposite side-disk through the agency of the cylindrical casing, which of course must be made of rigid material, as for instance strong sheet-iron or brass, iron-bars or the like. These 20 old constructions are objectionable in that the cylindrical casing, which should be merely provided for preventing separated magnetic material from adhering directly to the magnet and for conveying said material, 25 is moreover used for transmitting power. Therefore said cylindrical casing must be made comparatively strong and thick, whereby weakly magnetic material cannot 30 be well separated. In other machines heretofore known, the cylindrical screen is made of thin yielding material and the side-disks of the drum are connected mechanically by means of transmission devices located out- 35 side the drum.

In contradistinction to these old constructions and arrangements my present invention has for its object to provide an improved ore-separator, wherein the side-disks 40 of the drum-shaped screen are operatively connected to each other by means of devices arranged within the drum, said disks being connected at their peripheries by means of a casing made of very thin non-rigid material 45 and forming the drum. Therefore the cylindrical casing or screen is not used for transmitting power, one of the side-disks being actuated by means of a drive-pulley, while the other side-disk is actuated by the 50 first disk through the agency of a suitable gearing arranged within the drum. Thus it will be seen that the drum may be made of very thin and non-rigid material, as for instance linen, paper or the like, whereby the

materials to be separated may be brought 55 into the strongest zone of lines of magnetic force nearly without intermediate space, with the result, that the separator operates in a more perfect manner with a reduced 60 consumption of current.

The accompanying drawings illustrate one form of construction of my invention.

In these drawings Figure 1.— shows a longitudinal section of the improved separator, and Fig. 2.— shows a cross-section of same. 65

The core of the magnet 1 is provided with laterally projecting extensions 3, by means of which said magnet is secured in the well-known manner in stationary bearings 4, set-screws 5 being provided for adjusting said 70 magnet in the well-known manner. Current is brought to the separator through wires extending through a bore in the extension 3. Loosely arranged on the stationary extensions 3 are two side-disks 6, on 75 which is mounted a thin drum 2 secured by clampings 13 and each of which is provided with gear-teeth 7 at its inner periphery. Arranged on the stationary system of magnets 1, are small brackets 8, having bearings 80 for a horizontal shaft 9, carrying two toothed pinions 10 meshing with the gear-teeth 7 of the side-disk 6. Secured to the hub of one side-disk 6 is a wooden drive-pulley 11, which may be arranged on the 85 hub of the left hand or the right hand side-disk as desired. In the form of construction illustrated by way of example in the accompanying drawings, the drive-pulley or one of the side-disks 6 is driven by 90 means of a suitable transmission. The rotation of said disk 6 is transmitted by the gear-teeth thereof and through the agency of the toothed pinions 10 to the opposite side-disk 6. The cylindrical casing 2 of the 95 drum is made of very thin material as shown. The materials to be separated may be brought to the machine for instance by means of a conveying-belt 14, passing around the shaft 15. The non-magnetic 100 material drops immediately downwardly, while the magnetic material will be attracted and partly conveyed by the revolving drum to be received separately.

In the construction herein described, the 105 cylindrical casing of the drum may be easily and rapidly replaced by a new casing when worn away and the machine may im-

mediately be started again. The wearing of the cylindrical casing is without influence on the operation of the whole machine.

I claim:

5. A device of the kind described including a frame, a shaft fixed in said frame, an opposed pair of magnets supported fixedly from said shaft, bearing brackets fixedly mounted on said shaft a second shaft journaled in said brackets, spaced disks revolvably mounted on said first mentioned shaft, internal gears on the inner sides of said

disks, other gears on the second shaft meshing with said internal gears, means to rotate one of said disks, and a cylinder removably mounted on said disks and surrounding said gears and magnets.

In testimony whereof I have hereunto set my hand in presence of two witnesses.

GEORG RIETKÖTTER. [L. S.]
